UNITED STATES PATENT OFFICE

CHARLES I. NIELSEN, OF WEEHAWKEN, NEW JERSEY

LIFEBOAT

Application filed December 20, 1929. Serial No. 415,375.

The subject of my invention is a lifeboat for use on ocean-going liners, merchant ships, or warships which may be subjected to shell fire or boats of similar cellular design for aerial navigation made of suitable material for this branch of work.

Essentially, my invention consists in a boat having a sturdy hull divided with bulkheads to give it buoyancy to ride in a heavy sea. It is also an object of my invention to provide the lifeboat with two masts and with an engine and with means for controlling the engine and the sails and the steering from a single position, namely, a control cockpit.

A further object of my invention is to provide within the bulkheads a sealed compartment for the engine, a cabin for small children and a toilet compartment.

It is a further object of my invention to supply disappearing housing hooks on the lifeboat so that once the weight of the boat has been removed from the hooks there will be no chance for the tackle blocks which support the lifeboat to rehook.

For a more complete exposition of my invention reference may be had to the annexed drawings and specification at the end whereof my invention will be fully pointed out and claimed.

30. In the drawings,

Figure 1 represents an elevation showing the lifeboat under sail.

Figure 2 is a plan view, one half in horizontal cross section.

35. Figure 3 is a vertical cross section.

Figure 4 is a horizontal cross section taken at point below the tank deck or cellular under body of boat showing the entire buoyancy tank or cellular system.

40. Figure 5 is a vertical transverse cross section taken from directly in front of the control cockpit or other bulkhead.

Figures 6, 7 and 8 are, respectively, plan and side elevations of my improved housing hook.

Figure 9 is a partial horizontal cross section of a modified form of lifeboat suitable for warships.

45. Figure 10 is a vertical cross section of the modification shown in Figure 9.

My improved lifeboat has a hull built of any suitable material and will be a staunch, able, seaworthy boat designed in compliance with the U. S. Steam Ship Inspectors' Rules and Regulations as prescribed by law. To 55 give the lower body extra weight or to, in other words, hold the center of gravity down as low as possible a system of ballast tanks as shown in Figures 3 and 5 are located in the central part of the boat directly over the 60 keel. These tanks will have a pipe connection leading out through the bottom of the boat and a small air tube leading up to the tank deck for the release of the air in the tanks. As the boat immerses into the water 65 these tanks will all fill automatically to the water line of the boat and act as or constitute the ballast, tending to keep the boat always on an even keel.

In the main and central part of the boat, 70 as will be noted on Figures 3 and 4, are located a number of large size pipes that extend from well deck or tank top deck down through the bottom of the boat and will be made with the usual flood valves. These 75 pipes are used for automatic bailing of the boat in a heavy seaway and will also prevent the boat from going down by suction of a sinking vessel on which the lifeboat is carried, as these pipes relieve any vacuum from the 80 bottom of the boat.

The hull is also divided into compartments by water-tight bulkheads. The forward bulkhead 6 separates a forward compartment 7 from the remainder of the hull. Near the 85 stern of the boat there is provided a water-tight bulkhead 8 which cooperates with longitudinal bulkheads 9 and 10 (see Figure 4) to provide three compartments 11, 12 and 13 in the stern. The compartment 12, which 90 is the center one, contains the motor 14 and also an oxygen tank 15. If desired, means for starting the motor may be arranged so as to project from the central compartment through a water-tight bushing. The central 95 body of the hull between the bulkheads 6 and 8 is adapted to contain a large number of variously shaped tanks 16 which give buoyancy to the boat. In case of injury the water will enter the main or central part of 100

the boat, then and at no other time will these tanks come into play for buoyancy and it is for just such cases that these tanks are placed there. Above these air tanks is arranged the 5 horizontal deck 17 which supports a tank top deck 18 which in turn supports wearing strip floors 88. Above the deck 18 is arranged a series of transverse seats 19. Convenient to certain of the seats 19 on the gunnels are 10 oarlocks 20.

At the fore and aft portions of the boat are arranged hoisting hook housings 21 which are connected to the frame work of the hull by reenforcing members 22.

15 Housings 21 are adapted to contain hoisting hooks 23 of an improved design. Hooks 23 carry at the rear parts thereof counter-weights 24, which, when the weight of the boat is removed from the hooks 23 cause the 20 hooks to fall into position within the housings 21 and to assume the dotted line position shown in Figure 8. In this position hooks 23 are caught by latches 25 which are pressed by springs 25' and which latch hooks 23 in 25 such a position that the tackle-blocks cannot rehook on the hooks 23.

The upper portion of compartment 12 is provided with a water-tight manhole 26 whereby the compartment is carefully sealed 30 and the motor 14 protected against water. At the rear of the boat there is also provided a control cockpit 26' convenient to which is located steering wheel 27 which controls rudder 28 through a system of shafting 35 and gearing 129. Adjacent to control tower 26' is also provided lever 29 for controlling the connection of motor 14 with the propeller 30 so that the propeller may be actuated to drive the boat either forward or 40 backward.

There is also provided in the central portion of the boat masts 31 and 32 which are fitted into convenient mast chests 33 and 34 so as to be readily raised even by persons 45 unfamiliar with sails and boats. Mast 31 is provided with a fore staysail 35 and a schooner rigged foresail 36 and mast 32 is provided with a schooner rigged sail 37. Sails 35, 36 and 37 are provided with 50 convenient tackle for manipulating them. The halyards 38 for sail 37 are conveniently located to control tower 26'.

The forward compartment 7 contains bread tank 39, fuel oil tank 40 and a pair of buoyancy tanks 41 located, respectively, beneath tanks 39 and 40.

60 Compartment 11 is intended as a shelter for children or the most feeble members of the occupants of the boat. Compartment 13 may contain an electric stove for cooking and also the articles required by law to be carried in lifeboats, such as sea anchor, oil, waste, flares, compass, etc.

65 On either side of the hull there are mounted fenders 42, preferably of balsa wood, and

floats 43, also preferably of balsa wood, mounted on a rope.

The modification disclosed in Figures 9 and 10 is intended as a lifeboat for use with vessels subjected to shell fire. In this modification balsa wood 44 is substituted in place of the buoyancy tanks 16 shown in the first modification. Such a wood is extremely light and buoyant and will, therefore, serve to keep the lifeboat afloat even though struck 70 by shell fire. There is also disclosed in this modification a pump 45 adapted to be driven from the motor 14 in any desired manner.

I claim:

A lifeboat comprising a hull having at the 80 forward end thereof a water-tight compartment, a tank top deck, at the center of the boat a compartment containing means for buoying up the boat in case of injury to the boat that would permit the water to enter 85 the space below the tank top deck and at the stern three transversely spaced compartments the center of which has a water-tight closure and which contains a motor, a control cockpit, a steering wheel adjacent said control 90 cockpit, a control lever for said motor adjacent said cockpit for controlling said sail and all operations of the boat.

CHARLES I. NIELSEN.
